[57] CLAIM

The ornamental design for a combined suspended support for storage receptacle and hooks therefor, as shown and described.

DESCRIPTION

FIG. 1 is a front elevational view of a combined suspended support for storage receptacle and hooks therefor showing my new design, the rear being identical, the broken line showing of a receptacle being for illustrative purposes only;

FIG. 2 is a side elevational view thereof;

FIG. 3 is a top plan view thereof;

FIG. 4 is a partial sectional view taken in the direction of the arrows 4—4 of FIG. 3.

Fig. 1.Fig. 2.Fig. 3.

Fig. 4.
